UNITED STATES PATENT OFFICE.

WATSON F. QUINBY, OF WILMINGTON, DELAWARE.

HYDROCARBON-ENGINE.

SPECIFICATION forming part of Letters Patent No. 268,727, dated December 5, 1882.

Application filed April 20, 1882. (No model.)

To all whom it may concern:

Be it known that I, WATSON F. QUINBY, a citizen of the United States, and a resident of Wilmington, Delaware, have invented certain improvements in Hydrocarbon-Engines, of which the following is a specification.

My invention relates to certain improvements in that class of engines in which fluid hydrocarbon is vaporized into gas, mixed with air, and ignited in a closed chamber, the object of my invention being to construct a simple and effective engine of this class.

In the accompanying drawings, Figure 1, Sheet 1, is a sectional diagram of my improved engine; Figs. 2 and 3, views on a larger scale of the valve mechanism; Fig. 4, an enlarged view of the sliding cover-plate in the head of the working-cylinder; Fig. 5, an enlarged view of part of the oil and air supply pipes; Fig. 6, a diagram showing a modification of part of the invention; and Figs. 7 and 8, Sheet 2, views showing the method of making and applying the mica linings of the cylinders.

In Figs. 1 to 5, A represents a long cylindrical casing, which is divided by suitable transverse partitions into a working-cylinder, B, two pump-cylinders, D D', and a pressure-generating chamber, F, the latter communicating through a pipe, G, with inlet-chests a b on the pump-cylinders and inlet-chests d and e on the working-cylinder, said cylinders also having outlet-chests a', b', d', and e', respectively, which communicate with a discharge-pipe, G'. The pump-cylinders have air-inlet openings f and g and air-outlet chests f' and g', the latter communicating with a pipe, H, which terminates in a pipe, J, in the chamber F, said pipe J surrounding the oil-supply pipe K, and being perforated for the nozzles h of said pipe, and provided with openings i, adjacent to said nozzles, for the escape of air. Oil flows to the pipe K from a reservoir, M, which communicates at the upper end through a pipe, j, with the pressure-chamber F, this reservoir containing a snugly-fitting piston or float, k, of non-conducting material, which prevents the transmission of heat to the hydrocarbon below, the pipe j serving to equalize the pressure in the chamber F and reservoir M above the float, so as to permit the flow of oil to the nozzles h.

The ports of the various cylinders are controlled by valves m, actuated directly by the pistons n, all of which are connected to the same piston-rod, p, the piston n of the working-cylinder B being attached by a pivoted connection to the inner end of a rod, q, which passes through a slot in the head of the cylinder, and through a plate, s, which closes the slot, and is adapted to slide in guides on the cylinder-head to accommodate the movement 55 of the connecting-rod. The valves m are worked in pairs, so as to close a port at one end of a cylinder simultaneously with the opening of a port at the opposite end. The rods connecting the pairs of inlet-valves are outside 60 the casings of the cylinders; but the rods connecting the outlet-valves are adapted to casings t in the cylinders, the pistons n being recessed at the required points for adaptation to these casings, and the operation of the valves 65 being effected by the contact of the pistons with pins w, which project from the valve-rods through slots in the casings t or through the valve-ports.

It will be seen on reference to Fig. 1 that the 75 pumps D D' work alternately, so that a continuous supply of air is forced through the pipes H and J into the chamber F, where it combines with the hydrocarbon vapor from the nozzles h, the mixture of vapor and air being 80 then ignited, so as to generate in the chamber F pressure for operating the engine and pumps. It will be understood that a suitably-covered opening is made in the casing of the chamber F, so as to permit the ignition of the oil when 85 starting the engine. By generating pressure continuously and in a chamber separate from the cylinders regularity of working is insured, and the cylinders and ports do not become 90 choked with carbon, as when the gas and air are mixed and ignited directly in the cylinders.

I prefer to line the various cylinders of the engine with mica, which, in the case of the cylinders B, D, and D', may be fitted snugly thereto and secured by any heat-resisting cement. 95 In the chamber F the lining may be arranged, as shown in Fig. 8, so as to leave air-spaces between the same and the casing of the chamber.

The edges of the sheets of mica W are pro- 100

vided with interlocking projections, as shown in Fig. 7, so as to hold the sheets firmly in their proper positions.

In the modification shown in Fig. 6 two pressure-chambers are used, one of the pumps supplying air to one chamber and the other to the opposite chamber. In this case, although the generation of pressure in each chamber is intermittent, I still avail myself of the other advantages of separating the generating-chamber from the working-cylinders.

I claim as my invention—

1. The combination of the working-cylinder, the pressure-generating chamber, and the two pumps D D', working alternately, as specified.
- 15 2. The combination of the cylinders and their ports, the connected valves, the internal

casings, *t*, and the pistons adapted to actuate the valves, and recessed for adaptation to the casings, as set forth.

3. The combination of a gas-engine cylinder with a lining composed of sheets of mica having their edges interlocked, as set forth.

4. The combination of the generating-chamber *F*, the oil-pipe *K*, the reservoir with its piston *k*, and the pressure-equalizing pipe *j*, as set forth.

In testimony whereof I have signed my name to this specification in the presence of two subscribing witnesses.

WATSON F. QUINBY.
